INVENTOR:
FRANK J. STUART,
H. Woodward,

ATTORNEY.

UNITED STATES PATENT OFFICE

FRANK J. STUART, OF ST. LOUIS, MISSOURI

ABDOMINAL GARMENT

Substitute for application Serial No. 262,710, filed March 19, 1928. This application filed May 9, 1932.
Serial No. 610,224.

This application is a substitute for application 262,710, for Abdominal garment, filed by me March 19, 1928.

The invention has for an object to effect a novel construction of a garment having detachable leg pieces and aims particularly to provide a novel manner of attaching the leg pieces. While variously applicable, the present embodiment of the invention is particularly directed to improvements in abdominal belts and the like made of elastic materials, the belt portions of which it is undesirable to launder because of the rapid deterioration of the elastic threads which is caused thereby, and it is an object of my invention to enable the leg pieces to be properly attached in such a garment and easily removed for laundering. It is an especial aim to provide a fastening for such leg pieces in which a minimum service will be involved in repairing fastenings due to laundering.

Another important aim of the invention is to obviate the need for manipulating any element of the means by which the legs are fastened to the belt when the belt is removed or replaced upon the person. This is an important attainment in such appliances and eliminates the possibility of irksome delays and adjustments, faulty adjustments of the parts, and liability of discomfort generally.

A further aim of the invention is to present a non-elastic attaching means which will nevertheless accommodate itself to the wearer and to elastic action of the garment and permit the leg part to adjust itself and set comfortably upon the wearer without excessive strain at the connection locally or as a whole.

A further important aim of the invention is to provide a fastener of this kind which may be disconnected without the use of implements and may be likewise replaced.

Additional objects, advantages and features of invention reside in the construction, arrangement and combination of parts involved in the embodiment of the invention, as will be understood from the following description and accompanying drawing, wherein,

Figure 1 is a side view of a garment con-

structed in accordance with my invention, as worn.

Figure 2 is a detail of the garment opened out flat.

Figure 3 is a fragmentary detail of the connecting means. 55

Figure 4 is a detail of the fastening band.

Figure 5 is a horizontal sectional view of the belt with the leg part assembled thereon, parts being broken away to reduce the size of the view. 60

Figure 6 is an enlarged sectional view at the connection between the leg and belt.

Figure 7 is a fragmentary enlarged elevation of the loops and coengaged band. 65

There is illustrated an abdominal belt 10 which may be constructed in accordance with approved practices in garment of this nature, or other garments requiring leg pieces which it is desirable to have detachable. In the present instance, the belt comprises an abdominal supporter-reducer of elastic material, the ends of which are adapted to be connected by a lacing at the back of the wearer. Adjacent each extremity of the belt and spaced above its lower edge, one member 11 of a separable fastener is attached and at the front of the garment two similar parts 12 of separable fasteners are attached, these last two being preferably spaced equally from the medial vertical line of the belt. A leg piece supporting band or tape 13 is provided, which is of a length greater than that of the belt 10 at the lower edge, this band having parts 14 of separable fasteners at each end complementary with the members 11 on the belt, and toward the middle portion of the band two similar fastening members 15 are provided on the band complementary with the member 12. This linear measurement of material in the band between the members 15 exceeds the spacing of the members 12, and the material in the band between the members 14 and 15 exceeds in length the space between the fastenings 11 and 12. When in use on the person there is thus a slack portion in the band at the middle between the members 15, as at 13 in Figure 1, while sufficient slack is present in the end portions to permit the band to lie in zig-zag form in and between the loops 70

16 and 18, as shown in Figure 7. When the fastenings 14 and 15 are coengaged with 11 and 12, the middle portion of the band 13 extending between the members 15 will have a considerable amount of slack, as shown in Figure 2, whereby liability of binding of the band upon the person of the wearer is obviated. The corresponding greater lengths of the band between the fastenings 14 and 15 10 also provides a certain amount of slack which likewise obviates liability of this band binding upon the person and preventing the belt 10 from accommodating itself to the figure of the wearer through the functioning of the 15 elastic therein.

Between the fastenings 11 and 12 upon the belt, a series of uniformly spaced alined pendant loops 16 is attached, these loops being attached a distance above the line on which 20 the fastenings 11 are located, so that the lower ends of the loops fall adjacent the level of the fastenings 11, but stopping short of the lower edge of the belt a distance.

Leg pieces 17 are provided, the cut of 25 which is familiar in the making of garments of this kind. The form of each is such that the outer side extends upwardly and has an upper edge portion which may be alined with and secured to the lower edge portion of the 30 belt 10, the front and rear edges of this outer side of the leg extending continuously downward and inwardly, forming the crotch edge or upper edge of the inner side of the leg piece, which is of much less extent vertically 35 than the other side, as is familiar in such garments. The upper edges of the leg pieces may be hemmed in a simple manner and have attached thereto a series of loops 18 spaced at the same intervals as the loops 16, but extending upwardly so as to lie between the 40 loops 16. These lower loops in the present instance extend above the upper edge of the leg piece (although this is not essential) and are of such length that when they overlap 45 the loops 16 a distance corresponding to the width of the band 13, the top edge of the leg still will lie a suitable distance above the lower edge of the belt 10 to permit displacement of some or all of the loops 18 50 downward a distance and yet avoid any gap or opening there. Loops on the leg pieces and belt are overlapped as indicated, and the band 13 threaded through all, so that the leg is supported by the loops 18 upon the band, 55 and the latter is sustained by the loops 16. There is required only a very slight deflection of the band between the multiplicity of loops in order to take up a considerable amount of slack in the band. In the present 60 instance, the loops on the leg piece exceed the number of those on the belt by two, so that the two loops on the leg piece lie flat in front of the foremost loop on the belt inwardly of the fastenings 15 on the belt. This is due 65 to the fact that fewer supports are necessary

in front than at the back of the device, the greatest strain falling upon the connection between the leg and the belt at the rear. The number of loops may be otherwise varied. It may also be found desirable to vary the 70 spacing of the loops upon the belt progressively from the rear toward the front, making the spacing wider at the front, this being a matter of discretion. In the present instance, the loops are of such width and spacing as to form a practically continuous connection between the belt and the leg pieces which gives a very good appearance to the article. A detail which may be noted is the provision upon the front edge of the belt of 75 a reinforcement 19 which extends only a short distance over the front portion of the belt, depending from its lower edge, and being intended for use for the attachment of hose supporters. The front fastenings 15 80 upon the belt are preferably located inwardly of the ends of the reinforcement toward the middle of the belt, and the leg pieces are so arranged that they overlap the ends of the reinforcement so as to cover a hose 85 supporter fastening when attached, making further for the good appearance of my garment when worn. The fastening members 11—12—14—15 may be of any familiar snap action type of which there are numerous 90 kinds upon the market, and they do not require to be of large size or strength, because of the very slight strain which is applied to them by the nature of the supporting connection between the legs and the belt. 95 These fastenings usually include a small knob-like head on one member adapted to be pressed into a socket of the opposing element. The stress to which they are subjected will be transversely of this head. 100

The garment being assembled as described, the legs may be readily separated from the belt by simply lifting the members 14 and 15 from the members 11 and 12 on the belt, then grasping the band 13 at the loose portion between the fastenings 15, and drawing the ends of the bands outwardly through the overlapped loops until the loops on the leg piece and belt are left free to be drawn apart. It will be seen that there is no metal 110 fastening whatever on the leg pieces, so that they may be safely run through the laundry apparatus customarily employed in the ordinary wash. The leg pieces are ordinarily made of a material much cheaper than that of the belt, and may be readily replaced by new parts from time to time without any 115 work upon the belt.

Owing to the fact that the belt 10 becomes sciled very little while worn, and may be readily dry-cleaned, while the leg pieces require frequent laundering, my invention enables the ready utilization of separable leg pieces upon such a garment to good advantage where before no suitable connection of 120

- this kind had been available. The use of buttons is objectionable for many reasons, and lacks adaptability to vertical compensation in support of the legs of the garment.
- 5 Other known fastenings are similarly objectionable. With my construction, should one or more loops not be of the same length as the remainder and be out of line at their extremities, it will be readily apparent that in
- 10 the taking up of the slack of the band 13, such out-of-line loops will be prevented from taking more or less of the load in supporting the leg by a greater or lesser amount of slack of the band taken up thereby.
- 15 It will be seen that the utilization of my invention involves no impairment of functions in garments of this character, and its manufacture involves only ordinary sewing operations which may be performed by seam-
- 20 stresses.

I claim:—

1. In a garment of the character described, a waistline garment of elastic material having a multiplicity of pendant loops, a leg
- 25 member having an upper edge provided with upwardly extending loops to lie between those first mentioned, a non-elastic band tortuously engaged through all of the loops and a separable fastening connecting each end
- 30 of the band with a respective side of the waistline garment, said band being of a length greater than the normal spacing between the points at which its ends are connected to the waistline garment whereby circumferential variation of the size of the garment is permitted by variation of the angular relation of diagonal parts of the band.
- 35 2. The structure of claim 1 in which said waistline garment is an elastic belt element having ends separably connected, said band has two points of attachment by separable fasteners at each side of the waistline garment, the linear measurement of the band between the central two being greater than
- 40 the corresponding measurement of the waistline garment between its two central complementary fastenings, and the linear measurement of the band between the fastening elements on each end portion is greater than
- 45 the corresponding dimensions of the waistline garment between the respective complementary fastenings normally.
- 50

In testimony whereof, I affix my signature.

FRANK J. STUART.
